FUR PELT DRIER AND STRETCHER

Eugene Schulz, Sr., Merrill, Wis.

Application June 25, 1951, Serial No. 233,292

1 Claim. (Cl. 45—24)

1

My invention relates to fur pelt dryers and stretchers and more particularly to an improvement over my prior Patent 2,534,071 issued to me on December 12, 1950, for an Adjustable Fur Pelt Dryer and Stretcher.

A principal object of my invention is to provide a fur pelt dryer and stretcher frame including a pair of longitudinally extending side rods which may be adjusted for drying and stretching different sizes of pelts and which is particularly suitable for use with mink skins and the like.

Another object of my invention is to provide an adjustable fur pelt dryer and stretcher which may be used by the furrier in his shop for drying, stretching and holding skins when making mink scarves, etc., and one which may also be readily adapted to be used by the fur rancher or trapper during the pelting season.

A further object of my invention is to provide my fur pelt dryer and stretcher frame with longitudinally slidable hooks adjustably mounted on each side rod and which may be fastened to the hind feet portions of the pelt to hold the same in the proper position.

A salient feature of my invention is to provide a dryer and stretcher frame which may be adjusted to the desired size for the pelt required and which when inserted in the pelt may then be given an additional slight adjustment as may become necessary while the dryer and stretcher is in the pelt.

A still further object of my invention is to provide a simple practical and reliable construction that is economical to manufacture, easy to assemble and positive in its operation.

With these and other objects in view and to the end of attaining any other advantage hereinafter appearing, this invention consists in certain features of construction and combination and arrangements of parts, hereinafter described, pointed out in the claims and illustrated in the accompanying drawings.

In said drawings:

Figure 1 is a top plan view of my fur pelt dryer and stretcher and illustrating a form of my invention particularly suitable for use in the furrier's shop;

Figure 2 is a transverse section through the frame, taken on the line 2—2 of Figure 1 and looking in the direction of the arrows;

Figure 3 is a sectional view through one of the adjustable hooks and showing in detail the manner of securing the hook to one of the side rods;

Figure 4 is a fragmentary view partly in sec-

2

tion, showing further details of the adjustable hook, the section taken on the line 4—4 and looking in the direction of the arrows;

Figure 5 is a transverse section taken on the line 5—5 of Figure 1 and looking in the direction of the arrows;

Figure 6 is a top plan view similar to Figure 1, but illustrating a modified form of my fur pelt dryer and stretcher which is particularly suited to be used by the fur rancher or trapper;

Figure 7 is a top plan view of the type of dryer and stretcher illustrated in Figure 6, but showing a modified head portion.

Referring to the drawings in detail wherein similar reference characters designate corresponding parts throughout the several views, the letter A generally indicates one form of my improved fur pelt dryer and stretcher. The fur pelt dryer and stretcher A comprises a frame 10 which includes broadly side rods 11 and 12, head portion 13, tail portion 14, a head spreader 15 and the main adjustable spreader 16 secured adjacent the tail portion 14. Slidably mounted on each of the side rods is an adjustable hook 17.

These hooks 17 are identical and each includes a U-shaped clip 18 which extends around the side rod 12. Each end of the clip 18 is extended as at 19 and provided with openings into which a set screw 20 is received. The hook 17 is formed from a continuous length of relatively stiff wire, and the inner end of the hook is looped at 21 to pass around the shank of the set screw 20. A washer 22 is interposed between the head of the screw 20 and one of the members 19. It should be readily apparent from the above that by tightening the set screws 20, the hooks 17 may be firmly secured at any position on the side rods 11, 12.

In the form of the invention illustrated in Figure 1, it is desired that the head portion 13 of the dryer and stretcher frame be rounded by curving the end portions 23 of the side rods inwardly. This is desirable in that the rounded portion 23 of the head 13 will bear against the head mounting which the furrier expertly inserts into the head and nose portion of the pelt. The adjustable head spreader 15 includes a pair of transversely extending slotted ears 24 which are positioned in an overlapped relation as particularly illustrated in Figure 2 of the drawings. A bolt 25 is passed through the slot portions and a set screw 26 is utilized for frictionally securing the spreader at any desired position. The main spreader 16 is situated at the extreme tail portion of the stretcher frame and includes two

55

pivoted links 27, each of which is externally threaded and joined by a turnbuckle 28. Each link 27 is secured to one of the side rods by means of bolt 29. The extreme tail end of each side rod is flattened at 30 and provided with an opening through which the bolt 29 passes. The inner end of each link 27 is formed with a loop 31 which receives the shank of the bolt 29, and a washer 32 is inserted over the bolt and rests on the top portion of the link loop 31. The elements are then firmly secured in place by tightening down on the nuts 33.

For use in the furrier's shop, I also provide the tail portions of each side rod with thread opening 34. In using the dryer and stretcher described above, the furrier merely adjusts the upper and lower spreaders to the desired position and inserts the stretcher frame 10 into the pelt until the rounded head portion 13 rests against the head mounting. He then secures the hook 17 to the hind feet portions of the pelt and if desired, he may sew the rear portions of the pelt to the side rods by utilizing the openings 34 which are provided for that purpose. If the stretcher frame is too tight or if it is desired to increase the transverse width of the frame, the turnbuckle 28 of the spreader 16 is in a position at the tail portion so that it may be easily reached by the furrier without removing the frame from the skin, and further adjustment may be made as desired.

Referring now to the modifications illustrated in Figures 6 and 7 of the drawings, it will be noted that the dryer and stretcher frames 10' are practically identical to the stretcher frame 10, except that the thread holes 34 may be eliminated and the heads 13' are modified to make up for the lack of head mountings. The fur rancher or trapper is particularly concerned with stretching and drying the head of the animal so that the furrier will not experience difficulty in inserting the head mounting, artificial eyes, etc. I therefore provide upwardly extending portions 35 on the head 13' (Figure 6). These portions extend up into the head and nose of the animal and hold it in the desired position. The hooks 17' are identical to the hooks 17 and the head and tail spreaders 15', 16' are also identical to spreaders 15, 16.

The form as illustrated in Figure 7 of the drawings is identical to the form illustrated in Figure 6 with the exception of the head 13. In this instance the extensions 36 of the head 13 are not extended upwardly but are somewhat more pointed than the portions 23 illustrated in Figure 1 of the drawing. Here again the hooks 17' play an important part in securing the hind feet portions of the fur pelt. It is also to be noted that all of the bolts, set screws, etc., are provided with rounded heads so that they will not catch or tear the fur pelts during the insertion of the spreader frame into the skins.

From the foregoing, it is believed that the features and advantages of the invention will be readily apparent to those skilled in the art, and it will, of course, be understood that changes in the form, proportion and minor details of construction may be resorted to without departing from the spirit of the invention or the scope of the appended claim.

I claim:

In a fur pelt dryer and stretcher of the type comprising a pair of elongated side rods extending divergently from their tail ends toward their head ends, a transversely disposed spreader member connecting the side rods at a point adjacent and rearward of their head ends, and a second spreader member connecting the rods at their extreme tail ends, a pair of U-shaped clips, each clip extending around one of said side rods and having its opened end extending outwardly therefrom, a set screw extending transversely across said opening of each clip, and a pair of hooks, each hook having its inner end looped about said set screw, whereby each hook is slidably and adjustably mounted to one of said side rods.
